UNITED STATES PATENT OFFICE

GEORGE E. SMITH, OF PHILADELPHIA, PENNSYLVANIA, ASSIGNOR TO AMERICAN ENGINEERING COMPANY, OF PHILADELPHIA, PENNSYLVANIA, A CORPORATION OF PENNSYLVANIA

CRUSHER ROLL CONSTRUCTION

Application filed February 20, 1924. Serial No. 694,035.

My invention relates to crushers, having particular relation to rotary crushers applicable to furnace constructions.

One object of my invention is to provide a self-locking key comprising a body portion and a head portion which is adapted to be removed therefrom, the head portion being provided with a boss.

Another object of my invention is to provide a rotary crusher which is characterized by the fact that the teeth thereof may be readily removed and replaced with a minimum expenditure of time and effort.

A further object of my invention is to provide a rotary crusher comprising removable teeth and spring keys for locking the teeth in position, the keys having a head portion which is adapted to be broken off when it is desired to remove the keys and release the teeth.

A still further object of my invention is to provide a member having an aperture terminating in an enlarged base portion forming a shoulder, a plug element adapted to be loosely positioned in said aperture and provided with a locking shoulder for engagement with the first-mentioned shoulder, and a key for rigidly securing said shoulders in locking engagement, the key comprising a body portion positioned intermediate the plug element and the member and a head portion positioned outside of the aperture and provided with a boss for insertion in a recess formed in the plug element, the body portion being adapted to be moved into the enlarged base portion when the head portion is removed therefrom to permit of the withdrawal of the plug element from the member.

Other objects and applications of my invention, as well as details of construction and operation, whereby my invention may be practiced, will be clear from the following description, when taken in connection with the accompanying drawing, wherein

Figure 1 is a side elevational view of a ro-

tary crusher constructed in accordance with my invention;

Fig. 2 is a transverse sectional view taken on the line II—II of Fig. 1;

Figs. 3, 4 and 5 are top, side and end views, 50 respectively, of one of the removable teeth shown in Figs. 1 and 2; and

Figs. 6, 7 and 8 are top, side and end views, 55 respectively of one of the keys shown in Figs. 1 and 2.

In the illustrated form of embodiment of my invention shown in the drawing, I provide a rotary crusher construction, which is particularly applicable to coal-burning furnaces, comprising a power shaft 1 having a square portion 2, opposite parallel sides thereof being adapted to serve as supports for pairs of oppositely extending crusher teeth 3 and 4, respectively. 60

The pairs of crusher teeth 3 and 4, which may be of rectangular cross section, are loosely mounted in apertures 5 and 6 formed in clamping shell members 8 and 9, respectively. The inner surfaces of each of the shell members comprise vertical portions 11 and horizontal portions 12 which directly engage the sides of the shaft end portion 2. The horizontal and vertical portions 11 and 12 on opposite sides of the shaft portion 2 are provided with aligned perforations 13 and 14, respectively, which are adapted to receive clamping bolts 15, whereby the shell members 8 and 9 may be rigidly secured to the square portion 2 of the driving shaft 1. 65 70 75 80

The apertures 5 and 6 are provided with enlarged base portions 16 forming shoulders 17, 17' for reasons as will appear more fully hereinafter. The pairs of teeth 3 and 4 are provided with shoulder portions or locking lugs 18 on one side thereof which are designed for engagement with the shoulders 17. The shoulders 17 and 18 may be rigidly secured in locked engagement to avoid withdrawal of the pairs of teeth 3 and 4 from the 85 90

apertures or borings 5 and 6, respectively, by means of self-locking keys 19.

The keys 19 comprise a body portion 21, which is positioned between the side of the teeth away from the shoulder portion 18 and the adjacent side of the shell apertures, and a head portion 22, which is positioned outside of the apertures. The head portion 22 is provided with a pair of locking bosses 23 and 24 which fit into a transversely extending recess 25 formed in the adjacent surface of the teeth. The side of the head 22 opposite the bosses 23 and 24 may be beveled, as shown in the drawing, forming a supporting shoulder portion 24' which overhangs an edge portion 25' of the crusher shell member 9. The keys are preferably formed to have a predetermined spring action for reasons as will presently appear, and also consist of a material which may be fractured at will, whereby the head portion 22 thereof may be severed from the body portion 21 to permit of the latter being forced into the enlarged base portion 16 to effect the release of the wedged tooth.

In assembling the above noted parts, the shells 8 and 9 are first rigidly secured to the square portion 2 of the driving shaft 1 by means of the bolts 15. The pairs of teeth 3 and 4 are next positioned in the apertures or sockets 5 and 6, respectively, with the shoulder portions 18 thereof in locking engagement with the shoulder portions 17 of the shells 8 and 9. The spring keys 19 are then wedged in the space between the teeth and the walls of the apertures, as above set forth, the spring of the material of the keys 19 permitting an inward movement until the bosses 23 and 24 snap into the laterally extending tooth recess 25, thereby locking the key 19 rigidly in position.

If one of the pairs of teeth 3 and 4 should be broken during the operation of the crusher, the same may be readily removed and replaced without the heretofore additional necessary step of removing the clamping shells 8 and 9. This desired result is effected in my invention, as hereinabove described, by breaking the head portion 22 of the key 18, which is holding the broken tooth in position, from the body portion 21 and thereafter removing the body portion 21 to permit of the disengagement of the shoulders 17 and 18 and the removal of the broken tooth from the clamping shell.

When the head 22 is broken off, the body portions 21 may be pried out of the shell aperture. Or, if the body portion 21 should become wedged therein, it may be forced inwardly until it falls into the enlarged base portion 16 of the aperture in question, and is moved under the shoulder 17', as shown in dot-and-dash line in Fig. 2. Since the cost of each key 19 represents an exceedingly small amount as compared with the expense in-

70 cident to the replacement of the crusher teeth by the prior art methods, it may be ignored. After the removal of the broken tooth and the replacement of a new tooth, a new key is inserted, as hereinabove set forth.

75 While I have shown only one embodiment of my invention, for the purpose of describing the same and illustrating its principles of construction, it is apparent that various changes and modifications may be made therein without departing from the spirit and scope of my invention. I desire, therefore, that only such limitations shall be imposed thereon as are indicated in the appended claims or as are demanded by the prior art.

80 I claim:

85 1. In combination, a member having a socket provided with a recess, a second member mounted in said socket and provided with a locking portion inserted in said recess, said second member also having a recess, and a key securing said second member in its locked position, said key having a portion of substantially uniform cross section inserted in said socket, and a fracturable head portion 90 projecting from the socket, and said head portion having a boss inserted in the recess of said second member.

95 2. A rotary crusher comprising a socket having at the base thereof a shoulder-forming recess together with a second and oppositely arranged recess, a plug element inserted in said socket and provided with a locking shoulder portion engaging with said first-mentioned shoulder, and a spring key 100 securing said parts in position, said key comprising a body portion positioned within said socket and intermediate a wall of said socket and said plug element, and a fracturable head portion positioned outside of said socket, 105 said body portion of the key being displaceable from between said wall and the plug into said second recess when said head portion is removed to thereby permit retraction of the plug from the socket.

110 3. In combination, a member comprising a socket having a recessed base portion forming a shoulder, a plug element provided with a locking shoulder portion engaging with said first-mentioned shoulder, said element having a recess, and a key securing said parts in position, said key comprising a body portion of substantially uniform cross section positioned in said socket intermediate a wall of the latter and said plug element, and a 115 head portion positioned outside of said socket, said head portion being provided with a boss inserted in the recess provided in said plug element.

120 4. A rotary crusher comprising a shaft, a plurality of teeth, shells clamped to said shaft, said shells being provided with apertures having enlarged base portions forming shoulders, said teeth being positioned in said apertures and being provided with lock- 125

ing shoulder portions for engagement with said first-mentioned shoulders, each of said teeth being provided with a recess, and keys securing said teeth in the respective apertures 5 with the said shoulders in locking engagement, said keys each comprising a body portion of substantially uniform cross section positioned within said aperture and intermediate a wall of said aperture and said tooth, and a head portion positioned outside of said aperture and provided with a boss inserted in said tooth recess.
